UNITED STATES PATENT OFFICE.

WILLIAM H. EASTMAN, OF CONCORD, NEW HAMPSHIRE, ASSIGNOR OF ONE-HALF TO
HERBERT C. WHITNEY, OF PENACOOK, NEW HAMPSHIRE.

TELEPHONE INDICATOR.

Application filed June 1, 1922. Serial No. 565,172.

To all whom it may concern:

Be it known that I, WILLIAM H. EASTMAN, a citizen of the United States, and resident of Concord, county of Merrimack, 5 State of New Hampshire, have invented an Improvement in Telephone Indicators, of which the following description, in connection with the accompanying drawing, is a specification, like characters on the drawing 10 representing like parts.

This invention relates to an indicator for a telephone designed to give an indication to a party using the line whenever the receiver of some other party on the same line 15 is removed from its hook and to give the indication in such a way that the first-named party can tell which particular subscriber on the party line has removed his receiver from the hook and is attempting to listen in. 20 The invention is specially useful in rural districts where there are several subscribers on the same telephone line, because any subscriber who is using his telephone will be automatically informed as to which one of 25 the other subscribers on the line has removed his receiver from the hook and is attempting to use the telephone.

My improvement comprises a signal device attached to each telephone and arranged so that whenever the receiver is taken from the hook a signal will be sent over the telephone line giving the "ring" 30 number of the telephone being used. Therefore, whenever any subscriber takes his receiver off the hook a signal corresponding to his number will be sent over the line, and if the line is already in use, this signal will be received by the parties using the line and they will know who the intruder is.

40 In order to give an understanding of the invention I have illustrated in the drawings a selected embodiment thereof which will now be described after which the novel features will be pointed out in the appended claims.

Fig. 1 is a diagrammatic view showing the wiring in my improved indicator.

Fig. 2 is a top plan view of the support for the telephone receiver.

50 Fig. 3 is a side view thereof partly in section.

Fig. 4 is a front view.

Fig. 5 is a section on the line 5—5, Fig. 3. In the drawings I have illustrated the

parts of the telephone set largely in diagram.

1 indicates a transmitter of a telephone set, which is connected by a wire 2 of the local circuit to the winding 3 of the usual induction coil 4, the other winding 5 of said coil being connected in the telephone line 6. The coil 3 is also connected by the wire 7 to the battery terminal 8 to which the circuit 10 of the local battery 9 is connected, said circuit being also connected to the other 65 battery terminal 11. 12 is the receiver-supporting arm corresponding to the ordinary hook of a telephone set, said arm being pivoted at 13 and being acted on by a spring 14 which raises it when the receiver 16 is removed therefrom. When the receiver is supported on the arm 12 it forms a contact at 15 thereby closing the ringing circuit all as usual in telephone construction.

In carrying out my improvements I provide an indicating circuit in shunt with the local transmitter circuit and having an indicator therein and I also provide means for closing this circuit whenever the telephone receiver is removed from the arm 21.

The signal device comprises a buzzer 17 which is in a shunt circuit 18 connecting at one end to the terminal 19 of the induction coil and at the other end being connected to a plurality of contacts 20 which are insulated from each other. Co-operating with the contacts is a contact arm 21 pivoted at 22 and having a contact finger 23 adapted to move over the contacts 20 as the arm 21 turns about its pivot. This contact arm 21 is connected by a wire 24 to the battery terminal 11 and it is acted upon by a suitable spring 25 tending to turn it clockwise. The contact arm 21 is long enough to extend underneath the receiver-supporting arm 12 and the arrangement is such that when the receiver 16 is supported on the arm 12 the contact arm 21 will be in the position shown in Fig. 1. In this position the contact finger 23 rests on a block of insulation 26 and, 85 therefore, the circuit connected to the local battery 9 will be open. When the receiver is removed from the hook 12 the latter is raised by its spring 14, and when this occurs the spring 25 will swing the contact 90 arm 21 thus causing the finger 23 to wipe over the contacts 20. As this occurs the shunt circuit 18 will be closed and broken

95

100

105

again successively, thus causing an intermittent current to flow through the winding 3 of the induction coil and inducing a corresponding intermittent current in the line 5 wire 6. The movement of the arm 21 is controlled by a suitable dash pot 27, the piston 28 of which is connected to the arm 21 by means of a connection 29. The purpose of the dash pot is to retard the spring-10 impelled movement of the arm 21 so that the finger 23 will move over the contacts 20 slowly enough to give an intermittent signal.

The contacts 20 will be arranged to cause the indicator circuit to be made and broken 15 a number of times corresponding to the ring number of the telephone.

If, for instance, the ring number of the telephone is 3 then there will be three contacts 20, if the ring number is 5, there will 20 be five contacts, if the ring number is 22, then there will be four contacts, two of which will be wide contacts, and the others of which will be narrow contacts, so that as the finger 23 moves over the contacts two 25 long and two short signals will be given. The indicator 17 is in the nature of the familiar buzzer, so that as the finger 23 is on any contact a buzzing sound will be produced which will be transmitted over the 30 line 6 through the induction coil 4.

The arm 21 is also made use of to close the transmitter circuit and for this purpose I provide an additional contact 30 which is insulated from the contacts 20 and which is 35 connected to the transmitter by the wire 310 forming part of the transmitter circuit. This contact 30 is situated so that the finger 23 will come to rest thereon when the parts have reached the limit of their spring-im-40 pelled movement and at this time the transmitter circuit is closed through the wire 24, the arm 21, contacts 23 and 30. The shunt circuit 18 will also be open so that no signal will be transmitted over the line.

The housing or casing of the telephone instrument which is shown at 34 has secured to it a guiding member 35 having a slot 36 through which the end of the arm 12 extends and also having a vertical guideway 37 of a 50 size to receive the head 33 formed on the end of an arm or neck 32 extending from the receiver 16. This neck 32 may conveniently be formed on a split ring 31 which can be clamped to the receiver, thus providing a 55 structure which can be used with existing receivers. This guideway is open at the top, as shown at 38 and the guiding member is formed on its front face with a slot 39 adapt-60 ed to receive the arm 32. The head 33 is formed with two spring fingers or pawls 40 and one side of the guideway 37 is formed with ratchet teeth 41. The collar 31 is permanently secured to the telephone receiver and when the latter is to be placed 65 on the supporting arm 12 the head 33 will

be entered into the open upper end 38 of the guiding member 35 and will move downwardly in said guiding member and will engage the arm 12 in its downward movement and bring the latter to rest at the bottom of the slot 36 in a position shown in Fig. 3.

The lower end of the guiding slot 39 is widened as shown at 42 to permit the head 33 to be withdrawn therethrough when the 75 receiver is to be removed.

The purpose of the lever 41 and the spring fingers 40 is to prevent the receiver from being lifted upwardly in the guideway. When the head 33 has once entered the guideway it cannot be withdrawn in a vertical direction but can only be withdrawn by moving it clear down into the position shown in Figs. 3, 4 and 5 and then withdrawing it laterally through the enlarged opening 42. The fingers 40 will preferably extend slightly above the upper edge 43 of the enlarged opening 42 so that they will prevent the head 33 from sliding off from the end of the arm 12. To remove the receiver the latter is tilted slightly so as to swing the under side of the head 33 off from the end of the arm 12 and when this is done the fingers 40 will be disengaged from the upper edge 90 of the opening 42 and said head may be 95 readily withdrawn from the said opening.

I claim.

1. In a telephone, the combination with a transmitter and its local circuit, of a receiver-supporting arm which when depressed opens the local transmitter circuit and closes the ringing circuit and when raised opens the ringing circuit and closes the local transmitter circuit, an indicating circuit connected to the local transmitter circuit, an indicator in said indicating circuit, and means operative while the receiver-supporting arm is rising after the receiver has been removed but before the transmitter circuit is closed to close the indicating circuit. 100

2. In a telephone, the combination with a transmitter and its local circuit, of a receiver-supporting arm which when depressed opens the local transmitter circuit and closes the ringing circuit, and which when raised closes the local transmitter circuit and opens the ringing circuit, an indicating circuit connected to the local transmitter circuit, a buzzer in said indicating circuit, and means operative while the receiver-supporting arm is rising but before it closes the local transmitter circuit to alternately close and open the indicating circuit. 115

3. In a telephone having a transmitter and its local circuit and a receiver-supporting arm, the combination with said circuit and arm, of a shunt indicating circuit connected to the transmitter circuit, a plurality of separate contacts connected to said shunt 120 130

circuit in parallel, a contact-closing arm in said shunt circuit and adapted by its movement to wipe over the contacts successively, said arm normally being held inoperative by the receiver-supporting arm, and means to give said contact arm its operative movement when the receiver is taken off from its supporting arm.

4. In a telephone, the combination with a 10 casing having a slot, of a receiver-supporting arm extending through said slot, a guideway member secured to the casing and having a guideway extending at right angles to the arm, a collar adapted to be secured to 15 the receiver and having a head movable through the guideway to engage the receiver-supporting arm, and means to prevent retrograde movement of said head in

said guideway, the latter having an opening in its lower end through which the head 20 may be withdrawn.

5. In a telephone, the combination with a vertically-movable receiver-supporting arm, of a receiver having a laterally-extending neck and a head at the end of the neck 25 adapted to rest on said arm, a vertical guideway to receive the head, said guideway being constructed to permit freely downward movement of the head but to prevent upward movement thereof, and also having an 30 opening at its lower end through which the head can be laterally withdrawn from the arm.

In testimony whereof, I have signed my name to this specification.

WILLIAM H. EASTMAN.
